The ornamental design for note paper pad, as shown and described.

DESCRIPTION

FIG. 1 is a perspective view of note paper pad showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view showing the note paper pad sections spread apart with the top sheet partly detached at the tear line; and,

FIG. 9 is a right side elevational view with the second section of the note paper pad removed.
